CLAIM

The ornamental design for electroporation pipette as shown and described.

DESCRIPTION

FIG. 1 illustrates a front, right, perspective view of an electroporation pipette;

FIG. 2 illustrates a front elevation view thereof;

FIG. 3 illustrates a rear elevation view thereof;

FIG. 4 illustrates a right side elevation view thereof;

FIG. 5 illustrates a left side elevation view thereof;

FIG. 6 illustrates a top plan view thereof;

FIG. 7 illustrates a bottom plan view thereof;

FIG. 8 illustrates a front, right, perspective view of another embodiment of an electroporation pipette;

FIG. 9 illustrates a front elevation view thereof;

FIG. 10 illustrates a rear elevation view thereof;

FIG. 11 illustrates a right side elevation view thereof;

FIG. 12 illustrates a left side elevation view thereof;

FIG. 13 illustrates a top plan view thereof; and,

FIG. 14 illustrates a bottom plan view thereof.

(Continued)

The broken lines in the drawings depict portions of the electroporation pipette that form no part of the claimed design.
